UNITED STATES PATENT OFFICE

ROBERT BERTRAND CROSSGROVE, OF MIDDLESBROUGH, ENGLAND

DEVICE FOR SHARPENING SAFETY RAZOR BLADES

Application filed June 1, 1931, Serial No. 541,211, and in Great Britain June 6, 1930.

This invention relates to devices for sharpening safety razor blades.

It has been found that if the edge of a safety razor blade is rubbed on a glass, china or similar hard surface it is sharpened, and that if the surface is the inner surface of a tumbler or similar round hollow article, the blade is sharpened substantially at the correct bevel.

10 The object of the present invention is to provide a device for utilizing this effect.

In accordance with this invention I provide a blade holder for use in sharpening orificed safety razor blades, having two retaining members hinged together at one end, forming a clamp for gripping the blade, hooked means for hooking the apparatus to a curved sharpening member, and a projection on the clamp for limiting the angular 20 position of the blade during sharpening.

Two forms of device are illustrated in the accompanying drawings, wherein:—

Figs. 1, 2, and 3 are front, back and side elevations respectively, of one form of device.

25 Fig. 4 is a front elevation of a component member of another form of device.

Fig. 5 is a corresponding side elevation with the parts opened out for convenience of illustration.

30 Figs. 6, 7, and 8 are front, back, and longitudinal sectional elevations, respectively, of another component member.

Figs. 9 and 10 are front and back elevations, respectively, of the device in the closed or inoperative position.

Figs. 11 and 12 are side and front elevations respectively, of the device in the open or operative position.

40 In all the figures the razor blade is shown in dot-and-dash lines.

Referring to Figs. 1 to 3, the frame comprises a plate 1 on which the razor blade 2 is laid longitudinally. The plate is narrower than the blade so that the edges of the latter project from the side edges of the former.

45 When the blades are of the "Gillette" or three-hole pattern as illustrated, the plate 1 may be provided on its upper surface with two projections, pins, or the like 3, shaped and positioned so that they may engage the two end

holes 4 in said blades and prevent lateral and transverse movement of the blade relative to the plate.

A suitably bent wire guard 5 is hinged at 55 one end 6 to one end of the base plate 1 and is adapted to fold over the blade 2 so that the blade is rigidly disposed between the base plate and the wire guard.

The end 7 of the base plate remote from the hinge is extended beyond the end of the blade 2 and is embraced by a sleeve 8 adapted to slide longitudinally thereon so that the sleeve may engage the free end 9 of the wire guard 5 to retain the guard in position.

A projection 10 on the base plate 1 may engage a corresponding indentation or indentations 11, or vice-versa, on the sleeve 8 to retain it in the engaged and/or disengaged positions relatively to the wire guard 5. The extreme end of the base plate 1 is bent to form a 60 hook 12.

In use, when the blade 2 is disposed in the frame and effectually gripped therein as described the device is hung inside a glass tumbler or other similar article by means of the hook 12 engaging the upper edge of the tumbler. The edges 13 of the blade will then be disposed substantially vertical. If a finger is laid along the frame, the device then pressed against the surface of the tumbler, and the device is given a forward and backward movement around the inside of the tumbler, the edges 13 of the blade, which are in contact with the tumbler will be sharpened at the correct angle.

The base plate 1 may be provided on its under surface with a projection 14 or other device which will, when the device and blade are in position and pressed against the tumbler, abut against the inner surface of the tumbler and so limit the bending of the blade and thereby determine the accurate sharpening angle of the blade, the height of said projection from the base plate 1 being such as will effect this purpose.

The wire guard 5 will provide a convenient seat or cradle to accommodate the finger during the operation of the device, and each side thereof may be cranked or bent upwardly 100

at 15 to provide a more convenient seat or cradle.

A plate may be used instead of the wire guard 5.

5 The wire guard 5 may be provided with a rubber or other suitable covering, such as rubber tubing.

10 The depth of the projection 14 on the plate 1 may be such that, instead of limiting the bending of the blade, it may provide means for rocking the device during operation so that only the trailing edge of the blade is in contact with the tumbler.

15 The device may be constructed of metal, bone, celluloid, or other suitable material, or combination of materials.

20 The hook 12 may be lined with vulcanite or other suitable material 16 to provide a bearing surface for engaging the edge of the tumbler.

25 In the form illustrated in Figs. 4 to 12, the clamp comprises two plates 17, 18 hinged together at 19, the blade 2 being adapted to be disposed between them. One or both plates 17 and 18 may have projections 35 adapted to engage the holes 4 in the blade 2, whilst the other plate or plates may have co-acting recesses or depressions 36. The free end of one plate 17 is formed with a longitudinal 30 screw-threaded arm 20, whilst the free end of the other plate 18 is formed arcuately as at 21 so as to embrace part of the arm 20 on the plate 17.

35 The ends of the plates are adapted to be passed through a hole 22 in a transverse plate member 23 and secured thereto by a nut 24, spring, or clip engaging the screw-threaded arm 20. The transverse plate member 23 is preferably constructed of vulcanite or other 40 suitable material.

45 A substantially rectangular wire guard and stay member 25 is also hinged at one end to the hinged ends 19 of the clamp plates 17 and 18, the other end 26 being adapted to be passed over one end 27 of the transverse plate member 23, the sides 28 of the stay member 25 at or near to said end 26 of the stay member lying in slots 29, grooves, or recesses in the end of the plate member 23, so 50 that the whole device is made rigid.

55 The blade 2, plates 17 and 18, and stay member 25 are suspended in a tumbler by means of the transverse plate member 23 which rests horizontally on the edge of the tumbler, the dimensions of the plate 23 being such that the plate may slide on the edge of the tumbler to allow the blade to contact with the inner surface of the tumbler.

60 A finger is passed through the stay member 25 on to the plate 18 so that the blade 2 is pressed on to the surface of the tumbler, and back and forward motions of the device will sharpen the blade.

65 The component members of the device may be formed so as to be closely packed together

when not in use. For example, the transverse plate member 23 may be provided with a recess 30 on one side to accommodate the razor blade 2, and a recess 31 on the other side to accommodate the clamp plates 17 and 18 and the wire guard or stay member 25 folded together. A bolt 32 is passed through the central hole in the blade 2, the hole 22 in the transverse plate member 23, and central hole 33 in the clamp plates 17 and 18, and engaged by the nut 24 or spring clip on the other side to clamp all the parts together.

70 The free end 26 of the wire guard 25 may be cranked or bent at 34 so as to engage the screw arm 20 of the clamp plate 17 when folded together.

75 It may be found to be more effective to warm the tumbler before use, by immersing it in hot water, by breathing into it, or otherwise suitably, or the tumbler may be daubed with soap lather.

80 Furthermore the usual head and comb guard of a safety razor may be attached to the device in its closed position. For example, they may be laid on one side of the plate member 23, the usual central threaded pin on the razor head being passed through the members instead of the bolt 32 and secured by a nut.

85 A ferrule may be provided to engage the threaded pin on the razor head and the threaded arm 20 on the clamp plate 17, so that the clamp plates 17 and 18 may be utilized as the handle of the razor.

90 The device may be used for sharpening any type of safety razor blade, by suitably modifying the construction thereof. For example, the clamping plates may be provided with ribs and/or slots adapted to engage slots and/or ribs on the blades, so as to clamp said blades when they are provided with said slots and/or ribs.

95 What I claim and desire to secure by Letters Patent is:—

100 1. A blade holder for use in sharpening orificed safety razor blades, wherein the blade is clamped between two plates hinged together at one end, projections on said plates to engage holes in the blade, the ends of the plates being passed through a hole in a transverse orificed plate disposed substantially at right angles to the clamp plates and rigidly secured thereto by means engaging the end of one of the plates, and a wire 105 guard and stay member hinged at one end to the hinged ends of the clamp plates, the other end being passed over one end of the transverse plate, the sides of the stay member reposing in recesses in the transverse plate.

110 2. A blade holder for use in sharpening orificed safety razor blades, wherein the blade is clamped between two plates hinged together at one end, projections on said plates engage holes in the blade, the ends of the 115

plates being passed through a hole in a transverse orificed plate disposed substantially at right angles to the clamp plates and rigidly secured thereto by means engaging the end of one of the plates, a wire guard and stay member is hinged at one end to the hinged ends of the clamp plates, the other end being passed over one end of the transverse plate, the sides of the stay member reposing in recesses in the transverse plate, and the transverse plate being provided with a recess on one side to receive the blade and with a recess on the other side to receive the clamp plates and stay member folded together in the inactive position, a bolt being passed through the members and secured by a nut to hold the members compactly together.

3. A blade holder for use in sharpening orificed safety razor blades, having two retaining members hinged together at one end, forming a clamp for gripping the blade, hooked means for hooking the apparatus to a curved sharpening member, and a projection on the clamp for limiting the angular position of the blade during sharpening.

4. A blade holder for use in sharpening orificed safety razor blades, having two retaining plates hinged together at one end, forming a clamp for gripping the blade, hooked means for hooking the apparatus to a curved sharpening member, and a projection on the clamp for limiting the angular position of the blade during sharpening.

In testimony whereof, I affix my signature.
